PENCIL SHARPENER

Frank M. Schaefer, Chicago, Ill., assignor to
William G. Pankonin, Chicago, Ill.

Application February 20, 1941, Serial No. 379,789

15 Claims. (Cl. 120—96)

This invention relates in general to a pencil sharpener and has more particular reference to the cutters and the means for operating them.

An important object of the invention is therefore in the provision of improved cutters for sharpening a pencil and in the operating means for rotating the cutters.

Other objects of the invention are in the provision of an improved casing for housing the cutters and the motive means therefor; to provide an improved chip receptacle and means for removably holding it in place; to provide an improved pencil centering device operative for pencils of all sizes; to provide an improved enclosing casing of novel construction and design; and in general to produce the construction herein shown and described.

In the drawing illustrating a preferred embodiment of this invention,

Fig. 1 is a side elevation of a pencil sharpener in accordance with this invention;

Fig. 2 is a sectional view of the structure shown in Fig. 1;

Fig. 3 is a section taken on the line 3—3 of Fig. 2;

Fig. 4 is a section taken on the line 4—4 of Fig. 2;

Fig. 5 is a section taken on the line 5—5 of Fig. 2 showing one of the cutters; and

Fig. 6 is a perspective of a cutter supporting stem.

In pencil sharpeners as now commonly used the cutters are each made of one piece of material with spirally grooved blades which are both expensive and usually wear very rapidly so that the sharpener breaks the lead of a pencil or does not point it properly after a short use. These pencil sharpeners are also usually provided with an operative crank by means of which the cutters are turned.

In the present invention the cutters are improved by making them of a plurality of toothed discs assembled upon an arbor or sleeve and the motive means consists of a pull string operating a ratchet drum equipped with a return spring. By this construction the cutter discs can be suitably hardened so that they will wear less and the discs themselves can be changed from time to time so that those which wear more rapidly can be replaced by others which are not so worn. A single pull of the string is usually sufficient to point any pencil and the spring recoil of the string always returns it within the casing.

Referring now more particularly to the draw-

ing, a central standard or support 8 has a base 9 in which openings are commonly provided for attaching it to a horizontal or vertical support.

The outer portion of the standard provides a bearing bore 10 for a cutter shaft or spindle 11; a shouldered portion 12 at one side provides a circular seat for the inner end of an outwardly rounded casing 13; and an opposite circular projection 14 provides a seat for the inner circular end of a casing 15 which extends outwardly with an inwardly turned pencil opening 16 at its outer end. These two casing sections 13 and 15 together provide a somewhat streamlined outline of pleasing appearance rounded at one end and more pointed at the other.

A pair of cutters 17 are mounted at an angle upon spindles 18, the inner ends of the cutters being close together to provide a sharp point for a pencil. The spindles are inserted through outer ends 19 of a holder formed integral with or attached to the spindle shaft 11 which has a projection 20 near the bearing of the shaft into which the inner end of each spindle 18 is threaded.

To rotate the cutters a recess 21 is preferably formed in the standard and partially surrounding the spindle projection 20 and in the outer edge of this recess is seated a circular rack 22 having teeth on the inside. These teeth engage gears 23 carried by each of the cutters 17 so that as the spindle shaft 11 is rotated the gears 23 engaging the teeth of the circular rack 22 correspondingly rotate the cutter 17. As each cutter is slightly inclined to the axis of the shaft 11 the gears 23 will be correspondingly inclined to the ring gear 22 but the teeth are in proper alignment to produce rotation of the cutters.

Each spiral-like cutter 17 is preferably formed of a plurality of toothed discs 24. The discs 24 are substantially identical in size and configuration. In the preferred manner of construction they are punched out of thin metal stock and are subsequently heat-treated to harden their cutting edges. Each disc has a number of outer teeth 25 formed in the periphery of the disc. Each of these teeth presents a cutting edge when the disc is rotated in a counter-clockwise fashion, as viewed in Figure 5. The discs 24 have an inner or central opening provided with an internally projecting key 26. The discs 24 are concentrically arranged in laminated fashion on an arbor or sleeve 28. The arbor 28 is provided with a groove 27 which describes a spiral, or, more accurately, a helical path on its surface. One end of the arbor 28 has a projection 29. To this

projection the gear 23 is secured. When the discs 24 are assembled on the arbor 28 they abut against the projection 29 and the outer ends 19 of the cutter support. In the assembly, the keys 26 of the discs 24 fit in the groove 27 and as each disc is substantially identical and interchangeable, the adjacent teeth of adjacent discs will be slightly uniformly angularly misaligned to describe a spiral cutting path. Thus, as assembled, the cutter presents a plurality of spiral-like cutting edges. To change the discs on any arbor its bearing spindle 18 is simply removed by unscrewing it, the cutter being then bodily removable and the discs being changeable by simply removing them from the free end of the arbor and replacing the worn discs with others which are not subject to such severe wear. Thus the cutters may in effect be replaced or renewed and are capable of long life and hard usage without replacement of an entire cutter.

The shaft projection 20 is commonly provided with a pencil point extension 20a the extremity of which is just at the point where the cutters 17 would meet if extended, thereby limiting the feeding of a pencil therein and preventing the formation of a long thin point to the lead.

In the casing 15 below the cutters is a chip discharge opening 30 and a chip discharge receptacle 31 is positioned below the opening and held releasably but firmly in this position by an integral extension 32 which fits over the gradually reduced end of the casing, preferably having a portion 33 at the top and a perforated opening 34 at the end larger than the pencil opening 16 of the casing so that pencils may be inserted freely therethrough, the edge of the opening 34 being somewhat indented or turned inwardly so that this portion will also serve to center and maintain the extension 32 and the holding portion 33 in place. Between these portions the material may be omitted, forming serrated or other decorative edges 35 as shown more clearly in Fig. 1, which add to the completed appearance of the entire device. Also by having the extension and the holding portion separated in this manner they will spring more readily in place over the casing 15 and will hold the chip receptacle 31 tightly in place at the bottom of the casing.

At the inside of the casing 15 and pivoted to opposite sides of the extremity of the casing which form the pencil opening 16 are curved guides 36, the inner or free ends of which are drawn together by a coil spring 37 which extends entirely around both guides or is attached to the outer sides of both of the guides. This guide tends to center a pencil of any size with respect to the cutters 17 and to hold the pencil yielding in place by the tension of the spring 37.

To rotate the cutters by means of the shaft 11 a pull string ratchet mechanism is connected to the shaft at the side opposite the cutters. This comprises an end fitting 40 attached to the shaft by a set screw 41 and having a number of engagement notches 42 in a flange 43 at the end of the shaft. Freely rotatable on this end fitting 40 between the flange 43 and the shaft bearing formed by the standard 8 is a winding drum 44 preferably formed of sheet metal having an inner bearing portion 45 mounted on the member 40, an outer string receiving portion 46 with end flanges for preventing the string from running off the drum and with a connecting portion 47 at the outer side of the drum. Pivoted to this connecting portion and overlying and in line with the flange 43 are opposite weighted dogs or

latches 48 adapted to engage the teeth or notches 42 in the flange. The space under the drum and between the connecting portion 44 forms a container for a loosely wound coil spring 49 having one end attached to the drum by means of a screw 50 and the other attached to the standard 8 by a screw 51.

A pull string 52 is attached at one end to the drum, is wound on the outer portion 46 thereof, and the extremity extends through an opening 53 in the casing 13. The extremity of the string is provided with a knob or button 54 which will not pass through the opening and therefore forms a finger engaging means for the pull string and also limits the inward movement of the string thereby keeping it tightly wound on the drum. The casing 13 has a tightly fitting slip connection over the shoulder 12 and may therefore be rotated for positioning the opening 53 in any desired location, which requires some variation, depending upon the attachment of the device to a fixed support. The casing may also be removed for increasing or decreasing tension on the winding drum with respect to its spring 49.

In operation, assuming that the pencil sharpener is firmly attached to a suitable support, and that the chip receptacle is in place, a pencil is inserted through the opening 16 which is centered thereby with respect to the cutter 17. The operator grasps the pull string knob 54 and pulls outwardly on the string, which rotates the drum and with it the shaft 11 by reason of the engagement of the weighted catches 48 with one of the notches 42, thus rotating the cutters so that their gears 23 engage the inner teeth of the fixed ring gear 22 and rapidly rotate the cutters against the pencil inserted. The pull on the string is reduced and the spring 49 is allowed to reversely rotate the drum, returning the string within the casing and winding it upon the drum until the knob 54 engages the opening in the casing. One pull of the string is usually sufficient to point any previously pointed pencil but a number of additional pulls may be made if necessary. In the return movement of the string the latches 48 are thrown outwardly and are moved in a reverse direction so that they do not engage the notches 42 and therefore the shaft 11 and the cutters 17 are not reversely rotated, thus saving wear of all the parts.

The casings 13 and 15, as well as the chip receptacle 11 and its attaching parts, are represented as made of thin metal but may also be made of other material, either transparent or opaque, colored or clear, and may even be made of a molded condensite material such as Bakelite. The two casing sections are intended to form a substantially continuous outer surface separated only by a thin portion of the standard 8, presenting a novel and pleasing streamline outline.

I claim:

1. In a pencil sharpener, a support and a shaft rotatable therein and projecting to both sides thereof, rotatable cutters supported by the shaft at one side of the support, means for rotating the shaft at the other side of the support, a casing fitting over the mechanism and attached to the support having an opening for operating said means, and a casing extending over the cutters and secured to the support at the other side with a pencil opening at the end and a chip discharge opening at the bottom, the two casings forming substantially a streamline continuation each of the other.

2. In a pencil sharpener, a support, a shaft

rotatable therein and means for rotating it, cutters carried by the shaft at one side of the support, a casing secured to the support and extending over and beyond the cutters with a progressively smaller end having an inwardly turned extremity forming a pencil aperture, and means secured to the inwardly turned extremity within the casing to engage and center pencils of various sizes with respect to the cutters.

3. In a pencil sharpener, a support, a shaft rotatable therein and means for rotating it, cutters carried by the shaft at one side of the support, a casing secured to the support and extending over and beyond the cutters with a progressively smaller end having an inwardly turned extremity forming a pencil aperture, a pair of guides pivoted at opposite sides of each extremity, and a spring tending to pull the guides together at their free ends for centering a pencil with respect to the cutters.

4. In a pencil sharpener, a support, a shaft rotatable therein and means for rotating it, cutters carried by the shaft at one side of the support, a casing secured to the support and extending over and beyond the cutters with a progressively smaller end and having a chip opening at the bottom below the cutters, and a chip receptacle to fit closely below the opening having an extension fitting over the said end of the casing for holding the receptacle tightly but removably in place.

5. In a pencil sharpener, a support, a shaft rotatable therein and means for rotating it, cutters carried by the shaft at one side of the support, a casing secured to the support and extending over and beyond the cutters with a progressively smaller end and having a chip opening at the bottom below the cutters, and a chip receptacle to fit closely below the opening having an extension from the edge of the receptacle extending over the end of the casing and also for a distance on the side of the casing opposite the receptacle to provide a flexible holder and retainer for the receptacle.

6. In a pencil sharpener, a support, a rotatable shaft, means at one side of the support for rotating the shaft, a pair of cutters and means for mounting them on the other end of the shaft at an angle to each other and rotatable with the shaft, means for directing and holding a pencil for engagement of one end thereof between and by the cutters, each cutter comprising a plurality of similar discs with outer teeth and an inner key, an arbor on which the discs are mounted having a spiral groove engaged by the keys, and the discs being freely mounted and interchangeable on the arbor to replace worn discs at one location with other discs of the same cutter.

7. A structure in accordance with claim 6 in which the shaft has a cutter carrying head with spaced projections at angles to the shaft axis, and a removable spindle positioned in each pair of said projections upon which the arbor is mounted.

8. In a pencil sharpener, a cutter and means as

for rotating it, the cutter comprising a plurality of identically formed discs having cutting teeth on the periphery, and means for mounting the discs adjacent each other whereby adjacent teeth are slightly advanced angularly to form spiral cutting ridges with respect to the cutter.

9. In a pencil sharpening device, a main support upon which the device is mounted, an enclosing casing of somewhat oval shape also mounted on the support, the casing having an opening to receive a pencil, and a second casing mounted upon the first casing also having an opening for inserting a pencil.

10. In a pencil sharpening device, a main frame upon which the device is supported, an enclosing casing of somewhat oval shape, also mounted on the frame having an opening at one end to receive a pencil, and a second casing removably mounted upon the said end of the first casing having an opening through which a pencil is inserted, and also having a bottom chip receiving receptacle.

11. In a pencil-sharpener, a spiral-like cutter comprising a plurality of substantially identical toothed discs concentrically arranged in laminated fashion, adjacent teeth of adjacent discs being slightly uniformly angularly misaligned to describe a spiral path on the cutter, and means to secure said discs in said relation.

12. In a pencil-sharpener, a spiral-like cutter comprising an arbor having a spiral groove, a plurality of substantially identical discs having outer teeth and a central opening provided with a key, said discs being positioned in side-by-side relation on said arbor with their respective keys inserted in said groove whereby adjacent teeth describe a spiral path on the cutter.

13. In a pencil-sharpener, a spiral-like cutter comprising a plurality of toothed discs punched out to have the same configuration and be interchangeable alike, said discs being concentrically arranged in laminated fashion, adjacent teeth of adjacent discs being slightly uniformly angularly misaligned to describe a spiral path on the cutter, and means to secure said discs in said relation.

14. In a pencil-sharpener, a spiral-like cutter comprising an arbor, a plurality of substantially identical toothed discs concentrically arranged in laminated fashion, adjacent teeth of adjacent discs being slightly uniformly angularly misaligned to describe a spiral path on the cutter, and tongue and groove means of spiral configuration acting between said arbor and said discs.

15. In a pencil-sharpener, a cutter comprising an arbor, a plurality of toothed discs punched out to have the same configuration and be interchangeable alike, said discs being concentrically arranged in laminated fashion, adjacent teeth of adjacent discs being slightly uniformly angularly misaligned to describe a spiral path on the cutter, and tongue and groove means of spiral configuration acting between said arbor and said discs.
